UNITED STATES PATENT OFFICE.

JOHN G. PFADT, OF ERIE, PENNSYLVANIA, ASSIGNOR TO WILLIAM B. FLICKINGER, FRANK W. GRANT, AND JOHN G. PFADT, TRUSTEES, ALL OF ERIE, PENNSYLVANIA.

CENTRIFUGAL PUMP.

No. 897,483.

Specification of Letters Patent.

Patented Sept. 1, 1908.

Application filed February 23, 1905. Serial No. 246,936.

To all whom it may concern:

Be it known that I, JOHN G. PFADT, a citizen of the United States, residing at Erie, in the county of Erie and State of Pennsylvania, have invented certain new and useful Improvements in Centrifugal Pumps; and I do hereby declare the following to be a full, clear, and exact description of the invention, such as will enable others skilled in the art 10 to which it appertains to make and use the same, reference being had to the accompanying drawings, and to the letters of reference marked thereon, forming part of this specification.

15 My invention relates to improvements in multiple rotary pumps for raising and forcing water operating consecutively by centrifugal and impulsive force.

20 In multiple pumps having multiple impellers secured upon a common shaft in series, to obtain good practical results there should be a good communication between the sections forming the series, and such means for changing the direction of the 25 impelled currents under high velocity and constantly increasing pressure as to obviate as much as possible any churning of the liquid being pumped, and the loss of power caused thereby.

30 To this end my improvement consists in the features of construction hereinafter set forth and described, and illustrated in the accompanying drawings in which:

Figure 1 is a vertical section of a multiple 35 rotary pump embodying my invention. Fig. 2 is a transverse section of the same on the line $x-x$ in Fig. 1, looking in the direction of the arrow. Fig. 3 is a transverse section of the same on the line $y-y$ in Fig. 1, 40 looking in the direction of the arrow.

In these drawings illustrating my invention, A A' A² and B are sections forming the pump-shell. The sections A' and A² being divided by radial partitions C of a diameter 45 equal to the diameter of the impellers D which are secured to and driven by a shaft D', so that the impellers D operate in the chambers E between the walls C and the walls a. The chambers F on the opposite 50 sides of the partitions C are provided with radial partition walls f which divide the chambers F into sections. These partitions f are provided with curved extensions f' which extend over the peripheries of the 55 partitions C and across the chambers E out-

side of the peripheries of the impellers D so that the circular and centrifugal travel of the fluid thrown outward by the impellers D is deflected thereby sidewise over the peripheries of the partitions C into the chambers F and directed by the partition walls f therein in a direct line to the openings a' in the chamber walls a to be taken up by the succeeding impeller D until it is finally forced through the outlet B' of the pump.

60 In the drawings I have shown the walls or partitions f as straight radial ribs. It is obvious, however, that if desired they may be curved to any degree desired.

65 In operation the fluid is taken into the pump through the inlet a² and passes through the central opening a' in the wall a of the section A and thence is taken up by the first impeller D and forced outward against the curved partitions f' of the radial walls f, at 70 the peripheries of the impellers, in the first chamber E, and is deflected by said curved portions f' over into the first chamber F and downward between said walls f to the opening a' in the section A' from whence it is 75 taken by the second impeller D and again forced outward against the curved portions f' of the walls f in the second chamber F in like manner, and again travels inward to the central opening a' in the wall a of the section A² and thence it is taken by the impeller D in 80 the last chamber and forced out through the discharge B' of the pump.

85 In the drawings I have shown and described a pump having three impellers, but it is obvious that two or any number of impellers may be used as desired.

90 Having thus described my invention so as to enable others to make and use the same, what I claim as new and desire to secure by Letters-Patent of the United States is:

95 1. In a centrifugal pump, a pump shell having a chamber with a central inlet at one end and a central outlet at the other, a disk 100 forming a radial wall in said chamber, an impeller between said radial wall and the inlet end of said chamber, and deflector plates in said chamber extending over the periphery of the impeller and the periphery of the radial wall, on lines diagonal to the axis of 105 the impeller, substantially as set forth.

2. In a centrifugal pump, a pump shell having a chamber therein with a central inlet at one end and a central outlet at the other end, a disk forming a radial wall in said 110

chamber, an impeller between said radial wall and the inlet end of said chamber, and deflector plates in said chamber, portions of which are inclined to lines radial to the axis of the impeller, and extending longitudinally over the peripheries of the impeller and radial wall on lines diagonal to the axis of the impeller, substantially as set forth.

3. In a multiple stage centrifugal pump, a pump shell having two or more chambers therein, a disk forming a radial wall in each of said chambers, an impeller between the

radial wall and the inlet end of each chamber, and deflector plates in each chamber, extending over the peripheries of the impellers and radial walls therein, substantially as set forth. 15

In testimony whereof I affix my signature, in presence of two witnesses.

JOHN G. PFADT.
